CLAIM

The ornamental design for a GPS wireless dog fence device as shown and described.

DESCRIPTION

FIG. 1 is a front, top, and left perspective view of a GPS wireless dog fence device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, bottom, and right perspective view thereof.

The broken lines shown in the drawings represent portions of the GPS wireless dog fence device that form no part of the claimed design. The structural contour-indicating lines are for indicating the contours of the device, and are not surface ornamentation.
